C. G. SWEBILIUS

REPEATING FIREARM

Original Filed Feb. 9, 1925

Inventor:
Carl G. Swebilius,
By Lewis O. Fischman
Attorney.

UNITED STATES PATENT OFFICE.

CARL GUSTAF SWEBILIUS, OF NEW HAVEN, CONNECTICUT.

REPEATING FIREARM.

Application filed February 9, 1925, Serial No. 7,808. Renewed December 27, 1928.

This invention relates to firearms and more especially to magazine rifles of the take-down type.

An object of this invention is to normally maintain the cartridge ejector housed within a wall of the receiver and project it into the receiver when the breech bolt is in a predetermined position. The cleaning of the gun is thus facilitated as there is no projection for the cleaning rag to catch on.

A further object is a simple operating means for the take-down lock bolt.

An additional object is an improved sear operating spring.

According to this invention, the ejector is pivotally mounted in a groove in the receiver wall and is held retracted by a spring on which is provided a projection to be engaged by the breech bolt whereby the spring is tensioned to project the ejector into the receiver. The take-down lock bolt is operated by an eccentric mounted in the stock of the gun. The sear is operated by a leaf spring having a flat end resting on the bottom of the receiver.

Referring now to the drawings, Fig. 1 is a side elevation partially in section of a rifle embodying the invention, Fig. 2 is a horizontal section through the receiver with the breech closed, Fig. 3 is a similar view with the breech open, and Fig. 4 is a plan view of the sear spring.

A receiver 10 supports a barrel 11 from its front wall. A breech bolt 12 is reciprocally mounted in the receiver and is operated through the medium of an action rod 13. Slidably mounted in the breech bolt is a locking bolt 14 which seats in a socket 15 in the top wall of the receiver to maintain the breech bolt in breech closing position. The locking bolt, breech bolt and action rod are associated in the manner disclosed in the patent to Swebilius et al. 1,110,837 granted September 15, 1914.

A sear 16 is slidably and pivotally mounted in the receiver and has a portion 17 cooperating with the action rod 13 and a lug 18 cooperating with a shoulder 19 on the hammer 20 to prevent the unbreeching of the gun, all according to the disclosure in the aforementioned patent.

A leaf spring 21 has an end fitting in a slot in the sear 16. The other end of the spring 21 rests on the bottom of the receiver and is enlarged to extend the full width of the receiver. The spring is thus free to slide

when the sear is reciprocated and always exerts pressure to keep the lug 17 in contact with the action rod 13.

In one side wall of the receiver is cut a groove 22 in which is mounted a cartridge ejector 23. One end of the ejector is pivoted on a screw 24 and the other end is adapted to swing out into the receiver in position to eject a cartridge held by the extractor hooks 25. Also in the groove 22 is provided an operating spring 26 for the ejector. This spring comprises a resilient metal strip bent to form a short leg 27 and a long leg 28 which is substantially parallel to the short leg. A screw 29 passes through the bend of the spring and holds it in the groove. The end of the long leg fits in a slot in the pivoted end of the ejector and the end of the short leg bears against the bottom of the groove 22. In the long leg, is provided a hump 30 which projects beyond the groove.

In alignment with the spring 26, the breech bolt is provided with a short groove 31 near its rear end and a long groove 32 near its front end. One of the extractor hooks 25 is grooved to form an extension of the groove 32. This arrangement leaves a portion 33 of the breech bolt to engage the hump 30 as the breech bolt reciprocates.

The spring 26 normally exerts pressure on the ejector 23 to hold it within the groove 22 as shown in Fig. 2. As the breech bolt is moved rearwardly from the position shown in Fig. 2, the hump 30 is first received within the groove 31 and then engages the portion 33 of the breech bolt. The leg 28 of the spring 26 is thus forced into the groove 22 and the ejector rotated to bring it into cartridge engaging position. Further movement of the bolt brings the hump 30 into the groove 32 and allows the ejector to return into the groove 22. When the breech bolt is entirely removed from the receiver, the ejector is maintained in the groove 22. It is therefore out of the way and the gun can be cleaned without danger of the cleaner engaging the ejector and breaking it off.

The receiver 10 is open at the bottom and rear and is provided near its front wall with a pin 34 extending between its side walls. The stock 35 of the gun carries a projecting tang 36 having on its end a hook 37 adapted to engage the pin 34. In the upper wall of the receiver is a slot 38 in which is adapted

to seat the head of a bolt 39, slidably mounted in the stock to effect a locking connection therebetween when the hook 37 is engaged with the pin 34. A spring 40 bears against the bolt 39 in which is cut a slot 41 through which projects a rotatably mounted rod 42 having a button 43 on its end. In this rod is cut a groove 44 which is adapted to receive a pin 45 extending across the slot 41. When the pin 45 is received within the groove 44, the end of the bolt 39 is fitted in the slot 38 and the parts are locked together. Upon rotation of the rod 42 to engage its grooved surface with the pin 45, the bolt 39 is retracted and the parts may be separated.

When the gun is breeched, sear 16 is pulled forward to disengage the lug 18 from the shoulder 19 and the portion 17 engages a stop on the action rod 13 to prevent unbreeching of the gun, all according to the disclosure in said Patent No. 1,110,837. An aperture is provided in the tang 36 just ahead of the trigger 46. In this aperture is mounted a plunger 47 having one end adapted to contact with the under side of lug 18 and with the other end projecting beyond the under surface of the tang 36. A pin 48 on the plunger 47 fits in a groove in the wall of said aperture to prevent rotation of the plunger and a shoulder 49 prevents the plunger dropping through the aperture.

This plunger provides means whereby the gun may be unbreeched after being cocked. Upward movement of the plunger 47 lifts the rear end of the sear thereby rotating said sear about the pin 50 which engages its upper edge. The lug 17 is thereby disengaged from the stop on the action rod and the latter may be moved rearwardly to unbreech the gun. The plunger 47 is more conveniently placed and can be readily operated by the finger used to pull the trigger.

It is, of course, understood that various structural modifications may be made without departing from the spirit of the invention as set forth in the appended claims.

What is claimed is:

1. In a fire arm, a receiver having a groove in one wall, an ejector pivotally mounted therein, a spring tending to maintain said ejector in inoperative position, a hump on said spring, a breech bolt reciprocatively mounted in said receiver and means on said breech bolt to engage said hump to flex said spring whereby said ejector is moved into operative position. 60

2. In a fire arm, a receiver having a groove in one wall, an ejector pivotally mounted therein, a resilient strip bent to form a loop, 65 a pin passing through said loop, one end of said strip engaging one end of said ejector to maintain said ejector in said groove, a breech bolt reciprocatively mounted in said receiver and means on said breech bolt to flex 65 said spring whereby said ejector is moved into operative position.

3. In a fire arm, a receiver having a groove in one wall, an ejector pivotally mounted 70 therein, a resilient strip bent to form a loop, a pin passing through said loop, one end of said strip engaging one end of said ejector to maintain said ejector within said groove, a hump on said strip, a breech bolt reciprocatively mounted on said receiver and means on 75 said breech bolt to engage said hump whereby said strip is flexed to move the ejector into operative position.

4. In a fire arm, a receiver having a groove in one wall, an ejector pivotally mounted 80 therein, a resilient strip bent to form a loop, a pin passing through said loop, one end of said strip engaging one end of said ejector to maintain said ejector within said groove, a hump on said resilient strip, a breech bolt 85 reciprocatively mounted in said receiver, said breech bolt being grooved to receive said hump except for a short portion adapted to engage said hump whereby said resilient strip is flexed to move said ejector into operative 90 position.

In witness whereof I hereunto affix my signature this 20 day of Jan., 1925.

CARL GUSTAF SWEBILIUS.
